CLAIM

We claim the ornamental design for a bottle, as shown and described.

DESCRIPTION

FIG. 1 is a perspective view of a bottle showing the new design;

FIG. 2 is a front view thereof, the rear view being a mirror image thereof;

FIG. 3 is a left view thereof, the right side being a mirror image thereof;

FIG. 4 is a top view thereof; and,

FIG. 5 is a bottom view thereof.

The broken lines shown in the drawing views are included for the purpose of showing environmental structure that forms no part of the claimed design.
